UNITED STATES PATENT OFFICE.

ALBERT OPPENHEIM, OF NEW YORK, N. Y., AND EDWARD CLEARY, OF BRIDGEPORT, CONNECTICUT, ASSIGNORS TO THE CONNECTICUT WEB AND BUCKLE COMPANY, OF BRIDGEPORT, CONNECTICUT, A CORPORATION OF CONNECTICUT.

GARMENT-HANGER.

1,111,855.

Specification of Letters Patent. Patented Sept. 29, 1914.

Application filed March 21, 1914. Serial No. 226,221.

To all whom it may concern:

Be it known that we, ALBERT OPPENHEIM, a citizen of the United States, residing at New York, county of New York, 5 State of New York, and EDWARD CLEARY, a citizen of the United States, residing at Bridgeport, county of Fairfield, State of Connecticut, have invented an Improvement in Garment-Hangers, of which the following is a specification.

This invention has for its object to provide a garment hanger that will retain a garment securely in place so as to prevent it from dropping off when hanging or in handling, if no other garment is placed over it, and which, after a garment has been secured in place thereon, will receive another garment like an ordinary hanger. This we accomplish by providing a spring clip corresponding substantially in curvature with the upper side of the carrying bar and locking said clip in operative position by giving a partial turn to the suspending means. With these and other objects in view we have devised the novel garment hanger which we will now describe, referring to the accompanying drawing forming a part of this specification and using reference characters to indicate the several parts.

Figure 1 is a perspective showing the hanger with the clip locked in operative position; Fig. 2 a detail elevation showing the clip unlocked and raised above the carrying bar to permit a garment, as a vest or shirt-waist, to be placed upon the carrying bar; Fig. 3 a view partly in elevation and partly in section illustrating variations in the details of construction; Fig. 4 a detail plan view corresponding with Fig. 3, the shank 40 of the hook being in section on the line 4-4 in Fig. 3, looking in the direction of the arrows, and Fig. 5 is a view of the locking washer detached, corresponding with Fig. 3.

10 denotes the carrying bar which may be made of wood and is curved in the usual manner, and 11 the spring clip which is adapted to engage the upper side of the carrying bar, is made somewhat shorter than the carrying bar and has imparted to it a curvature having a shorter radius than the curve of the carrying bar, so that when released it will spring upward at the center and the pressure upon the carrying bar or on a garment thereon will be relieved. The

hanger is ordinarily suspended by means of 15 a hook 12 having a shank 13 which passes through a hole 14 at the mid-length of the spring clip and passes through or nearly through the carrying bar, in which it is secured against longitudinal movement but is 20 left free to rotate. In Figs. 1 and 2 we have shown the shank as secured in the carrying bar by forming a circular groove 15 in the shank and driving a pin 16 transversely through the carrying bar and in engagement 25 with the groove in the shank. In the form illustrated in Fig. 3, the end of the shank is passed through a locking washer 17 and then headed on the outer side of the washer, and longitudinal movement of the shank is prevented by a disk 18 which is counter-sunk in the under side of the carrying bar and is provided with lugs 19 projecting at right angles to the plane of the disk, which are adapted to pass through recesses 20 in the 30 locking washer and to engage the wood of the carrying bar so as to lock the washer against rotation and also to retain the shank of the hook against longitudinal movement, the heading of the shank, indicated by 21, 35 lying between the washer and the disk. 22 denotes a slot at the mid-length of the spring clip, which extends from hole 14 longitudinally of the clip. The shank is provided a short distance above the top of 40 the carrying bar with a locking projection 23, which may be formed as in Fig. 2 from a piece of wire bent to U-shape and one or both ends thereof rigidly seated in the shank, or if preferred the locking projection may be formed as in Fig. 3 by forcing metal of the shank outward by means of a blow upon a punch or by a drop hammer.

The operation will be obvious from the drawing. The spring clip is unlocked by turning the shank so as to place the locking projection in alignment with the slot, which will permit the mid-length of the clip to spring upward, as indicated in Fig. 2 and by dotted lines in Fig. 1. A garment, as a vest, shirtwaist or dress, is then placed over the hanger in the usual manner, the clip swung over it, as in Fig. 2, then the central portion of the clip is pressed downward until the locking projection has passed through the slot, and then the shank is given a partial turn to place the locking projection in engagement with the outer face of

the clip and hold it in the locking position, as in Figs. 1 and 3. This will retain the garment securely in place and will permit another garment to be placed outside thereof if required. To release a garment held in place by the clip, the shank is turned to place the locking projection in alignment with the slot and the clip will at once spring upward in the center, as in Fig. 2 and in dotted lines in Fig. 1, leaving it free to be turned out of the way by rotating it on the shank. It should be noted furthermore that until the shank and clip are placed so as to bring the locking projection into alignment with the slot, the clip will be supported out of operative position by the locking projection so as not to interfere with the placing of a garment upon the carrying bar.

Having thus described our invention we claim:

1. A garment hanger comprising a carrying bar, a hook having a shank rotatable in the bar and upon one side a locking projection, and a spring clip adapted to engage the upper side of the bar and having a hole at its mid-length through which the shank passes and a slot through which the locking projection may pass, the clip being locked in operative position by rotation of the shank to place the locking projection out of alignment with the slot and in engagement with the outer face of the clip.
2. A garment hanger comprising a carrying bar, a hook having a shank rotatable in the bar and upon one side a locking projection formed by displacing metal of the

shank outward and a spring clip through which the shank passes and which is provided with a slot through which the locking projection may pass, substantially as described, 40 for the purpose specified.

3. A garment hanger comprising a carrying bar, a hook having a shank rotatable in the bar and upon one side a locking projection, a locking washer seated in the carrying bar and provided with recesses, the shank passing through said washer and headed on the outer side thereof, a disk outside the washer and having lugs passing through the recesses and engaging the bar, 50 whereby the washer is held against rotation and the shank against longitudinal movement, and a spring clip on the upper side of the bar through which the shank passes and which is provided with a slot through 55 which the locking projection may be passed.

4. A garment hanger comprising a carrying bar, suspending means comprising a shank rotatable in the bar and having upon one side a locking projection and a spring 60 clip through which the shank passes and which is provided with a slot through which the locking projection may be passed and which upon rotation of the shank will engage the outer face of the clip.

In testimony whereof we affix our signatures in presence of two witnesses.

ALBERT OPPENHEIM.

EDWARD CLEARY.
